[57] **CLAIM**

The ornamental design for a scale with display, as shown and described.

DESCRIPTION

FIG. 1 is a top view of a scale portion of a scale with display according to my novel design;

FIG. 2 is a bottom view of a scale portion of a scale with display according to my novel design;

FIG. 3 is a front view of a scale portion of a scale with display according to my novel design;

FIG. 4 is a rear view of a scale portion of a scale with display according to my novel design;

FIG. 5 is a left side view of a scale portion of a scale with display according to my novel design;

FIG. 6 is a right side view of a scale portion of a scale with display according to my novel design;

FIG. 7 is a perspective view from above of a scale portion of a scale with display according to my novel design;

FIG. 8 is a perspective view of a connected scale and display portion of a scale with display according to my novel design;

FIG. 9 is a front view of a display portion of a scale with display according to my novel design;

FIG. 10 is a rear view of a display portion of a scale with display according to my novel design;

FIG. 11 is a top view of a display portion of a scale with display according to my novel design;

FIG. 12 is a bottom view of a display portion of a scale with display according to my novel design;

FIG. 13 is a left side view of a display portion of a scale with display according to my novel design;

FIG. 14 is a right side view of a display portion of a scale with display according to my novel design;

FIG. 15 is a perspective view from above of a display portion of a scale with display according to my novel design;

FIG. 16 is a perspective view from above of a display portion of a scale with display according to my novel design;

FIG. 17 is a front view of a display portion of a scale with display according to my novel design with the LCD being switched on; and,

FIG. 18 is a perspective view of a connected scale and display portion of a scale with display according to my novel design with the LCD being switched on.
